CHARLES F. LAMBERT, OF GROSSE POINTE, MICHIGAN, ASSIGNOR, BY MESNE ASSIGNMENTS, TO CLAYTON & LAMBERT MANUFACTURING COMPANY, OF DETROIT, MICHIGAN, A CORPORATION OF DELAWARE

TORCH STRUCTURE

Application filed December 19, 1927. Serial No. 240,961.

This invention relates to torch structure and has to do particularly with that type of torch known as a hand blow torch and comprising a container, pressure creating means 5 and a generator and burner structure supported by the container.

Heretofore torch structures of the hand blow torch type have been of somewhat standard structure as to general features and 10 principles of operation, such torches being usually provided with a fuel container tank comprising a base and provided with a suitable handle, a suitable pump for creating pressure within the tank, and a fuel conducting conduit for conducting the fuel under pressure towards the generating and burner structure. In creating the torch blast and in generating and maintaining vaporization it has been customary to eject the vaporized, 15 but unmixed fuel, directly from a valve controlled jet block into the burner nozzle where the vaporized fuel mixes with the air to form a combustible mixture, the point of combustion taking place at such a point as to 20 heat a portion of the fuel conducting means whereby to tend to vaporize the same. Some torches of this type, although being very hard to initially start, have been very satisfactory 25 during the first fifty to seventy hours of operation as long as the control valve is open 30 to produce a relatively large blast of flame. However, it has been practically impossible in torches of this type to graduate and control the flame, thus making it necessary to 35 either provide a large blast of flame or none at all. Furthermore, torches of this type present a great problem as to carbonization, 40 and most practical torch structures are provided with various unique arrangements to permit cleaning of the various parts made necessary by the formation of carbon.

It is the object of the present invention to 45 provide a novel torch structure wherein the generation of the fuel is efficiently and accurately controlled in such a manner as to produce any flame desired from an intense blast down to substantially a pilot flame, the generation being so controlled as to substantially 50 prevent any carbonization of the fuel in any

part of the generator structure whether such fuel be kerosene or gasoline.

A further object of this invention is the provision of a torch manifold and burner structure wherein the generated fuel is mixed 55 after being projected from the jet block, and it is then conducted in its combustible form, in three different directions. In other words, the vaporized fuel is projected forwardly of the generator, mixed to form a combustible 60 mixture, then directed rearwardly and then forwardly again where it is ignited to form a blast.

Another feature of the present invention 65 relates to the provision of a novel generating tube in combination with the burner structure wherein the fuel in a limited part of the generator tube is heated by a portion of the mixed fuel vapor after the fuel vapor has 70 been directed rearwardly of the burner structure, the generator tube being of such structure and so arranged as to maintain vaporization even when the torch flame is 75 reduced to practically a pilot flame.

Another feature of this invention has to 80 do with novel starting structure wherein the starting of the torch structure is accelerated by directing the initially vaporized fuel issuing from the generator tube back against the generator in the form of a blast.

Still another feature relates to the compact 85 design and arrangement of generator and torch structure and the positioning of the same relative to the fuel structure whereby to present a balanced torch structure as a unit.

Other novel features will be brought out 90 in the specification and claims.

In the drawings:

Fig. 1 is a front elevation of a torch structure embodying the features of my invention 95 and illustrating particularly the compact arrangement and balancing of the various parts.

Fig. 2 is an enlarged vertical sectional view 100 taken through the generator and burner structure of the torch shown in Fig. 1 and illustrating in particular the preferred form of the generator tube, the starting device, and the manner of changing the path of movement of the generated and mixed fuel.

Fig. 3 is a horizontal cross sectional view taken through the structure shown in Fig. 2 and illustrating the spacing of the mixing chamber from the generator tube, and the manner of directing a portion of the vaporized fuel against the enlarged part of the generator tube to effect and maintain vaporization.

Fig. 4 is a cross sectional view taken on line 4—4 of Fig. 2.

Fig. 5 is a view similar to Fig. 2 but illustrating a modified form of starter structure.

Fig. 6 is a horizontal cross section taken along the center of the generator tube, of the structure shown in Fig. 5.

Fig. 7 is a cross sectional view taken on line 7—7 of Fig. 5.

Fig. 8 illustrates a further modified form of my invention and showing in particular the manner of directing the main portion of the fuel forwardly and deflecting a portion of the vaporized mixed fuel rearwardly to heat the generator tube.

Fig. 9 is a plan view in section of the structure shown in Fig. 8.

Fig. 10 illustrates a further modified form of my invention similar to the structure shown in Figs. 2 and 5 but so arranged whereby the vaporized portion of the generator tube is heated directly by the flame issuing from the main burner nozzle.

The present invention is directed to torch structures where the main result desired is a confined blast of flame and wherein the entire structure is preferably formed in a compact, sturdy, and well balanced manner. The base of the structure may vary considerably, and in the various drawings I have shown various modifications of my generator starter and burner structure, but it will be understood that the invention in general relates broadly to a novel head or burner structure for a blow torch of the type described.

As best illustrated in Fig. 1, the fuel tank, which is generally designated 1, may be of the standard type and is provided with a suitable base 2, handle structure 3, and pump assembly 4. The generator and burner structure is generally made up of a generator tube 5, a burner head 6, manifold 7 and burner outlet 8. These parts, due to their novel design and arrangement present a relatively long burner structure, and for this reason I have provided a fuel supporting conduit 9 which extends upwardly at an angle from the torch tank 1 whereby to balance the complete burner structure with respect to the tank which forms the base of the torch. This presents a very compact torch structure as a unit, and at the same time such torch structure is well balanced so that the weight is centrally positioned with respect to the base.

As best shown in Fig. 2, the fuel conduit 9 terminates in a burner head 6 and this burner head 6 is provided with a suitable valve seat

10 and tapered valve member 11 whereby the control of the fuel to the generator and burner is at a point remote from the burner structure; or, in other words, the liquid fuel is shut off or controlled at a point where it is still raw liquid fuel.

The generator tube 5 is adapted to fit into the head 6, one end of the generator tube being reduced in diameter and the other end of the generator tube being enlarged, as at 12.

The end of the generator tube is provided with a standard jet block 13 and the burner valve is provided with a suitable stem 14 which extends the length of the generator tube and terminates in a suitable cleaner needle which is adapted to project through the orifice of the jet block when the valve 11 is seated against the valve seat 10.

A suitable coiled wire extends the length of the generator tube and is positioned immediately around the valve stem 14, a second coiled wire is positioned around the first coiled wire but only extends the length of the enlarged part 12 of the generator tube.

This enlarged part of the generator tube is adapted to be positioned adjacent the heating means, as will be later described.

By enlarging the generator tube it will be obvious that a greater area and a relatively thin film of liquid fuel is initially presented to the front of and adjacent the surface of the generator tube for initially starting, and during the operation of the device it will further be obvious that raw liquid fuel will be fed through the smaller part along the helical passageway, and that this raw liquid will expand as it comes to the hottest part of the generator tube, which is the enlarged part, having a plurality of helical passageways.

This small part and large part of the tube are so designed as to prevent accumulation of too much raw fuel, and by providing for the natural expansion of the fuel all back pressure is eliminated and the burner is prevented

from "running cold." This insures that all the fuel issuing from the jet block will be efficiently vaporized. Furthermore, when the valve is turned off to close down the torch the closing off point is remote from the generator and at the point where the liquid fuel is raw and relatively cold, and by reason of the end of the generator tube being large and being hot, and the two rows of coiled wires forming a capillary passageway, all the liquid fuel will be drawn out from the generator tube and be vaporized upon passing through the enlarged part of the generator whereby to substantially prevent all carbonization in the generating tube.

The end of the generator tube and jet block may be positioned in a suitably apertured extension 15 which may, as shown in Figs. 2 and 3, form an extension of an integral manifold and burner casting. This casting may comprise the inlet mixing chamber 16 which

is spaced from the end of the jet block, a conduit 17 for conducting the mixed gases rearwardly of the torch, a second conduit 18 for conducting the mixed gases forwardly of the torch, and a burner nozzle 19 for directing the blast of flame forwardly. The manifold 17 preferably extends rearwardly in the same plane as the mixing chamber 16 of the generator tube whereby the inner wall thereof, as at 20, may be perforated or provided with a suitable burner opening whereby to direct a portion of the gases, passing through the manifold, against the enlarged portion of the generator tube in the form of flames. This manifold and burner housing may be secured to the burner head 6, as at 21, but it will also be obvious that such manifold and burner may be formed in separate parts and secured to the burner head in any suitable manner.

A priming cup 25 is pivotally mounted beneath the generator tube, as best shown in Figs. 2 and 4, and the forward part of such priming cup is preferably provided with an upturned portion 26 which serves as a blast deflector to deflect the vaporized fuel initially issuing from the jet block back against the generator in the form of a blast of flame to accelerate the heating and starting of the generator. This combined blast deflector and priming cup may also be used for initially filling the priming cup with liquid fuel, as by opening the valve 11. When the torch is cold liquid fuel will flow through the generator out through the jet block and be deflected down into the priming cup by the deflector 26. The combined deflector and priming cup may be suitably held in position by a pivoted member 27, or by any other suitable means, and when the generator is hot enough to maintain continued vaporization the priming cup and deflector may be dropped down into position by moving the member 27 to one side wherein the vaporized fuel will pass from the jet block into the mixing chamber 16 of the manifold 7. This manifold, which is shown integral in Figs. 2, 3 and 4, is preferably so shaped as to completely bend the vaporized fuel 180° and direct the same rearwardly, as best shown in Fig. 3. This rearwardly directed portion 17 of the manifold then extends upwardly near the rear end of the generator tube, and then preferably at right angles whereby the portion 18 of such manifold is positioned just above the generator tube, as best shown in Fig. 4. This portion 18 again directs the fuel vapors forwardly of the torch and through a suitable perforated burner member 28. Beyond the burner member 28 the portion of the manifold 18 terminates in the burner nozzle 19 which forms the ejecting or exit nozzle for the torch blast.

In operation, the liquid fuel in the tank 65 having been placed under pressure by

means of the pump 4, the valve may be opened to admit the raw fuel under pressure into the generator tube where it will feed in a helical path towards the jet block from where it will be projected against the baffle member 26. When sufficient fuel has been deflected into the priming cup (which in the case of gasoline need be only a very small amount), the valve 11 is closed and the fuel is ignited. Due to the large surface area of the enlarged part of the tube and the relatively thin film of liquid fuel in this large area, the fuel in the enlarged part of the tube is quickly heated and is projected in the form of a vapor out through the jet block against the deflector 26 and backwardly over the top of the fuel in the priming cup and against the generator. As this fuel vapor comes in contact with the open flames from the liquid fuel it will be ignited and be projected against the tube in the form of a blast of flame. This rearwardly directed blast will also pick up fuel from the priming cup and thus accelerate the burning of the fuel in the priming cup. This strong blast will quickly heat the enlarged part of the generator tube and in a very short time the priming cup may be dropped to allow the vaporized fuel to be projected into the mixing chamber 16.

If desired, and particularly when kerosene is being used, the valve may be slightly opened after the starter has been in operation for a short time, and this will greatly increase the blast which is directed rearwardly against the generator tube. This will create a very intense blast and heat the enlarged part of the tube to a point where the thin film of liquid fuel will be completely vaporized. After the priming cup is dropped the fuel vapor will be projected through the mixing chamber 16, directed rearwardly by the manifold 17 and then upwardly and forwardly by the manifold 18. A small portion of the fuel vapors will pass through the burner 20 and be projected against the enlarged portion of the generator tube. These fuel vapors may be ignited artificially, or preferably automatically by any flame which might be rising from the priming cup. The main portion of the fuel vapors will pass through the burner 28 and will be ignited in the burner nozzle 19. The burner 28 will prevent the flames from traveling backward. It will be obvious that the valve 11 may be opened to any extent desired to produce an intense blast, or may be throttled down whereby the flame issuing from the nozzle 19 may be reduced to a pilot flame. During operation of the torch, as the liquid passes the valve 11, it will enter the smaller part of the generator tube, which is remote from the auxiliary flame and the main blast, and will be conveyed in a spiral path towards the large part of the tube. As the raw liquid fuel approaches the enlarged part of the

5 tube, and gradually comes in contact with the heated walls and the double series of heated coils, it will gradually expand. The enlarged part of the tube will take care of this expansion and at the same time convey 10 the partially vaporized fuel, under pressure and by capillary action, through the hottest part of the enlarged part of the tube where it will be completely transformed into a dry fuel vapor.

15 A modified structure shown in Figs. 5, 6 and 7 is quite similar to the structure illustrated in Figs. 2 and 3 with the exception that the blast deflector, which may be designated 30, is formed and mounted separately from the priming cup, the priming cup, in the embodiment shown, may be designated 31 and is preferably formed integral with the manifold and burner nozzle. 20 The space between the end of the generator tube and the mixing chamber is of course open, as at 32 to admit air for combining with the fuel vapor in the mixing chamber. The deflector shown is 25 preferably vertically pivoted, as at 33, and is thus adapted to be swung into and out of position merely by moving the handle 34. The operation of this device, shown in Figs. 5 and 6, is precisely as that described in connection with Figs. 2 and 3 although in the structure shown in Figs. 5 and 6 it will be obvious that the liquid fuel might be initially projected into the fuel pan even if the deflector 30 will be in its outward position.

30 The structure shown in Figs. 8 and 9 is somewhat similar to the structure shown in Figs. 2 and 5, the main difference being that the vaporized fuel is projected directly forwardly of the torch after it leaves the jet block, and only a portion of such vaporized fuel being deflected rearwardly to serve as an auxiliary flame, whereas in the other structures illustrated the main body of fuel vapor vaporized is projected forwardly, 35 rearwardly and again forwardly. In the structure shown in Figs. 8 and 9 the fuel conduit 9 is similar to the other fuel conduits, and it terminates similarly in a burner head 6. A mixing chamber, which may be 40 here designated 40, is spaced from the end of the generator tube but it leads directly into an integrally formed burner nozzle 31 which is separated from the mixing chamber by a suitable burner screen, or perforated burner member 42. Leading from the mixing chamber 40 is an auxiliary burner manifold 42 which is formed integrally with the members 40 and 41, but which is preferably, 45 as shown, connected with an auxiliary burner 43 in the form of a separate tube. This auxiliary burner member 43 is slotted, as at 44, and is provided with a cylindrical screen member 45, which serves as a burner member for the slot 44 whereby the fuel vapor passing rearwardly through the manifold 42 is

50 directed against the enlarged part 12 of the generator tube. A fuel pan 46 is preferably integrally formed with the mixing chamber 40 and extends rearwardly underneath the generator tube, as best shown in Fig. 8. A 55 horizontally pivoted blast deflector 47 is adapted to be swung into or out of position in front of the generator tube whereby to deflect fuel vapors rearwardly against the generator tube in the same manner as the blast deflectors shown in Figs. 2 and 5. The 60 operation of this modified structure, shown in Figs. 8 and 9, is analogous to the operation of the structure shown in Figs. 2 and 5, the main exception being that the main portion of the fuel vapor is projected directly forward of the torch and out through the burner nozzle 41 in the form of a blast while only a small portion of the vaporized mixed fuel is deflected rearwardly through the 65 manifold 42 to perform its function of heating the enlarged portion of the generator tube.

65 In the modification shown in Fig. 10 the general structure of the burner apparatus is quite similar to that shown in Figs. 2 and 3. This similarity extends to the mixing chamber 16 at which point the manifold extends upwardly, as at 50, and terminates in a forwardly directed manifold 51 which is positioned at a distance rearwardly of the enlarged part of the generator tube. This manifold portion 51 terminates in a burner nozzle 52, and a burner screen or perforated burner member 53 is positioned at a point just rearwardly of the enlarged part of the generator tube. This modification differs from the other structures, particularly wherein the enlarged part of the generator tube is heated indirectly by the means of the main blast in the burner nozzle 52, as combustion will take place at a short distance in front of the burner screen 53. It will be obvious that this torch structure, as shown in Fig. 10, may be regulated and turned down low just as in the previous structures disclosed and described, as the enlarged part of the generator tube will present a relatively large surface and a relatively thin film of fuel to be heated, and even if the flame within the burner nozzle 52 is turned quite low it will still create enough heat adjacent the large part of the generator tube to maintain complete vaporization, the relatively small passageway in the rear end of the generator tube preventing the back pressure and preventing the generator tube from "running cold."

70 It will thus be seen that I have provided a torch structure which may be started in a very short period of time, in which the fuel is positively vaporized and mixed before entering the burner nozzle, and in which a portion of the fuel vapor is preferably caused to move in three different directions before 75 leaving the burner nozzle as a working blast. 80

This not only presents a compact hand torch which is extremely easy to operate and may be turned down to practically a pilot flame, but it will be obvious that such structure substantially prevents all carbonization in the generator tube and burner head. Furthermore, it will be obvious that I have provided a very compact and efficient torch which is so positioned relative to the container tank as to present a well balanced unit.

What I claim is:

1. The method of starting, generating and conducting liquid fuel in torch structures of the type having generating tubes, which comprises passing liquid fuel through a generator tube, entrapping and heating a portion of the same while in the tube to expel the generated fuel therefrom, deflecting fuel vapors initially issuing from the tube backwardly against the tube to accelerate starting of the same, and then directly conducting the fuel vapor issuing from the generator tube backwardly and directing only a small portion against the generator in the form of flames for maintaining vaporization.

2. The method of starting, generating and conducting liquid fuel in torch structures of the type having generating tubes, which comprises entrapping a quiescent mass of liquid fuel in the tube, heating the same, and then initially accelerating generation of the fuel in the tube by deflecting the fuel vapor initially issuing therefrom backwardly against the same in the form of a blast of flame, and then twice completely reversing the direction of movement of the vaporized fuel before issuing the same in the form of a torch blast.

3. The method of starting, generating and conducting liquid fuel in torch structures of the type having generating tubes, which comprises entrapping liquid fuel in the tube, cutting off the source of supply, heating the trapped liquid to expel same as vapor, initially accelerating generation of the fuel in the tube by deflecting the fuel vapor initially issuing therefrom backwardly against the same in the form of a blast of flame, opening up the source of supply and then twice completely reversing the direction of movement of the vaporized fuel before issuing the same in the form of a torch blast, a portion of said reversed fuel vapor being directed against the generator to maintain vaporization of the fuel therein.

4. Torch structure, comprising a tank, a fuel conduit carried thereby and in turn supporting a burner head, a single generating means connected at the end to said head, a burner nozzle, a manifold spaced from the other end of the generating means for conducting vaporized fuel to the nozzle, and means in said burner head for controlling the supply of liquid fuel from said conduit, through said head, to said generating means.

5. Torch structure, comprising a tank, a fuel conducting conduit carried thereby, and generating and burner structure carried by the fuel tank, said generating means comprising a tube having a portion of its length of relatively small diameter, and a portion of relatively large diameter, means within the tube for feeding the liquid fuel therethrough by capillary action, and means for deflecting a portion of the vaporized fuel from its normal path and for directing flames in heat conducting relation with the portion of the generator tube of relatively large diameter whereby to maintain vaporization of the liquid fuel.

6. Torch structure, comprising a tank for receiving and placing liquid fuel under pressure, a supply conduit, a burner nozzle, a generating tube positioned between the tank and the burner nozzle and connected at its inlet end with the supply conduit by means of a valve, and a manifold for connecting the outlet of the generating means and the burner nozzle, the inlet end of said manifold being in axial alignment with the generating tube and terminating in a mixing chamber spaced from the end of the generating tube.

7. Torch structure of the type having a container tank for receiving liquid fuel and placing the same under pressure, comprising in combination a generator tube having a shut-off valve at its inlet end, and means for feeding by capillary action the liquid fuel therethrough, and a jet block at the other end, a manifold spaced from the jet block for conducting the generated fuel forwardly, rearwardly, and then again forwardly of the torch, and a blast deflector adapted to be positioned in front of the jet block for initially deflecting fuel vapors issuing from the generator back against the same to accelerate starting thereof.

8. Torch structure of the type having a container tank for receiving liquid fuel and placing the same under pressure, comprising in combination a generator tube having a shut-off valve at its inlet end, and means for feeding by capillary action the liquid fuel therethrough, and a normally unrestricted jet block at the other end, a manifold for conducting the generated fuel forwardly, rearwardly, and then again forwardly of the torch, and a blast deflector adapted to be positioned in front of the jet block for initially deflecting fuel vapors issuing from the generator back against the same to accelerate starting thereof, said blast deflector being pivotally mounted to permit the fuel vapors to pass through the manifold.

9. Torch structure of the type having a container tank for receiving liquid fuel and placing the same under pressure, comprising in combination a generator tube having a shut-off valve at one end, and means for feeding by capillary action the liquid fuel

therethrough, and a jet block at the other end, a manifold for conducting the generated fuel forwardly, rearwardly, and then again forwardly of the torch, and a blast deflector adapted to be positioned in front of the jet block for initially deflecting fuel vapors issuing from the generator back against the same to accelerate starting thereof, said blast deflector being pivotally mounted to 10 permit the fuel vapors to pass through the manifold, the shut-off valve at the entrance of the generator tube being adjustable whereby to modify the torch blast from an intense blast to substantially a pilot flame.

15 10. Torch structure of the type having a tank base for receiving liquid fuel and placing the same under pressure, comprising in combination a generator tube having an inlet end of relatively small diameter, and 20 an outlet of relatively large diameter, a mixing chamber spaced from the outlet end of the generating tube for mixing the fuel vapor into a combustible liquid before conducting the same to the torch nozzle, and means for 25 heating a portion of the enlarged part of the generator tube only for maintaining vaporization of the liquid fuel, whereby the liquid fuel will enter the small end of the generator tube in raw form and gradually expand as it 30 is heated.

11. Torch structure, comprising in combination a burner nozzle, a completely independent generator tube, a combined manifold and mixing chamber spaced from the 35 end of the generating tube for conducting fuel vapor to said nozzle, a priming cup positioned beneath the generator tube, a blast deflector adapted to be moved to a position between the end of the generator tube 40 and the entrance of the mixing chamber, a valve control means positioned at the entrance of the generator tube for controlling and graduating the torch flame by controlling the amount of fuel fed to said generator tube, 45 and an auxiliary burner positioned alongside said generator tube for heating same during normal operation of the torch.

12. Torch structure of the type having a tank base and fuel conduit projecting therefrom, 50 comprising in combination a generator tube projecting forwardly, a mixing tube spaced from the end of the generator tube for conducting the generated vapor forwardly of the torch, a manifold for conducting the fuel vapor rearwardly and alongside a portion of the generator tube, and then forwardly towards the burner nozzle, a portion of said manifold adjacent said generator tube being apertured to permit a portion of the fuel vapor 55 to be projected against the generator tube.

13. Torch structure of the type having a tank base and a fuel conduit projecting therefrom, comprising in combination a generator tube projecting forwardly of the torch, a mixing tube spaced from the end of the generator 60

tube for conducting the generated vapor forwardly of the torch, a manifold for conducting the fuel vapor rearwardly and alongside a portion of the generator tube, and then forwardly towards the burner nozzle, a portion of said manifold adjacent said generator tube being apertured to permit a portion of the fuel vapor to be projected against the generator tube, valve structure adjacent the end of said generator tube for controlling the supply of liquid fuel therethrough to control the torch blast without materially affecting the directing of a portion of the fuel vapor against the generator tube.

14. Torch structure of the type having a tank base and a fuel conduit projecting therefrom, comprising in combination a generator tube projecting forwardly, a mixing tube spaced from the end of the generator tube for conducting the generated vapor forwardly of the torch, a manifold for conducting the fuel vapor rearwardly and alongside of the portion of the generator tube, and then forwardly towards the burner nozzle, a portion of said manifold adjacent said generator tube being apertured to permit a portion of the fuel vapor to be projected against the generator tube, valve structure adjacent the end of said generator tube for controlling the supply of liquid fuel therethrough to control the torch blast without materially affecting the directing of a portion of the fuel vapor against the generator tube, 80 85 90 95

100 105 110 115 120 125 130

10. Torch structure of the type having a tank base for receiving liquid fuel and placing the same under pressure, comprising in combination a generator tube, a torch nozzle, and means spaced from the end of the generator tube, a manifold for conducting the generated and combustible fuel forwardly, rearwardly alongside the generator tube and again forwardly in three separate paths of movement before the fuel is ignited at the torch nozzle.

16. Torch structure, comprising a container tank forming the base as well as the container, a generator tube and burner structure for conducting the raw fuel and generated fuel in the same direction, a valve head at the entrance end of the generator tube for supporting the generator and the entire burner structure, and a supply tube connected to said valve head and projecting downwardly at an acute angle to the generator and burner structure, said supply tube being secured to the top of the tank at approximately the center thereof, whereby to more evenly distribute the weight of the generator and burner structure with respect to the tank.

In testimony whereof I affix my signature.

CHARLES F. LAMBERT.
